HYDRAULIC ELEVATORS

Kenneth R. Rosenberg, 8536 N. Pelham Parkway,
Milwaukee, Wis. 53217
Filed Mar. 4, 1966, Ser. No. 531,895
6 Claims. (Cl. 187—1)

This invention relates to improvements in hydraulic elevators, and more particularly to a novel safety device which is adapted to prevent the entry of water into the hydraulic oil system of an elevator.

Hydraulic elevators of the type herein concerned include an elongated cylinder or plunger housing which extends downwardly below the basement or lower level of the building, and an extensible ram or plunger carried in and projecting above said cylinder is designed to raise and lower the elevator cab through the actuation of a hydraulic pump assembly, there being a shallow pit adjacent said cylinder to house other necessary components. Unfortunately, after a period of use it is not uncommon that the packing and sealing members surrounding the extensible plunger and other movable elements become worn and oil leaks from the hydraulic system and accumulates in the pit, thus fouling the pit and affecting the safe operation of the elevator. To overcome this objectionable situation, most modern elevators have a ring member mounted on and surrounding the upper end or head of the cylinder which is designed to collect oil which leaks from the system and runs down or drips from the plunger, and mounted therebelow is a tank or reservoir which is adapted to receive the leakage oil from said collecting ring. A float-type switch is carried within said oil return reservoir and is so designed that when the accumulated leakage oil reaches a certain predetermined height in said reservoir a pump is actuated to return said oil to the hydraulic system of the power unit, thus ensuring that there is always a sufficient quantity of oil in the system to permit safe operation of the elevator.

Such conventional safety devices are satisfactory for their intended purpose but, unfortunately, one of the greatest dangers in hydraulic elevators is that water which forms on the plunger as condensate, or surface water which finds its way into the area, will enter the oil return reservoir and be pumped into the power unit hydraulic system, where it will saponify the oil. In such instances when the jelly-like saponified oil is circulated in the hydraulic system it can clog the filter and valve members and cause a failure which can result in uncontrolled movement of the elevator. Such occurrences are not uncommon, and have been the cause of tragic accidents.

With the above in mind, the principal object of the present invention is to provide a novel sensing device for mounting in the oil return reservoir of a hydraulic elevator system which is adapted to detect the presence of water in said reservoir. In the event water is present said sensing device is designed to automatically actuate an associated switch to halt the operation of the oil return pump, thereby preventing said water from being pumped into the power unit hydraulic system, and the operation of the elevator is also halted, except to allow said elevator to descend to the lowermost level to discharge its passengers.

A further object of the present invention is to provide a novel safety device adapted to prevent the entry of water into the oil system of a hydraulic elevator, as described, which device is relatively simple and inexpensive

2

in design and construction, which is reliable in operation, and which device is otherwise particularly well adapted for its intended purposes.

With the above and other objects in view, which other objects and advantages will become apparent hereinafter, the invention comprises the improved elevator safety device described in the following specification and also any and all modifications or variations thereof as may come within the spirit of said invention, and within the scope of the appended claims.

In the accompanying drawings, wherein there is illustrated one preferred embodiment of the invention, and wherein the same reference numerals designate the same parts in all of the views:

15 FIG. 1 is a perspective view showing the oil-collecting ring, return reservoir, and the control housing, with a part of said housing broken away to show the water-sensing device and associated components mounted therein; and

20 FIG. 2 is a front elevational view of the water-sensing probe device featured in the present invention.

25 Referring now more particularly to FIG. 1 of the drawings, the numeral 10 designates the steel flange or ring which is rigidly mounted in surrounding relationship on the head portion of the plunger cylinder (not shown)

in conventional hydraulic elevators. As hereinabove mentioned, said ring 10 is designed to collect oil which might leak from the hydraulic system and drip or flow downwardly on the plunger, as frequently happens when the plunger oil seals and packings become worn. Secured 30 on said collecting ring 10 by means of bolt and nut assemblies 11 are a pair of depending support brackets 12, and suspended thereon is a return oil reservoir 13 and control housing 14. Extending downwardly into said reservoir 13 from the collecting ring 10 is a tube 16 which 35 is designed to direct the leakage oil accumulating in said ring downwardly into said return reservoir.

40 Mounted within said reservoir housing 13 is a float switch 17 which is vertically-adjustably suspended from the top of said housing, said float member having an upright rod portion 19 which projects upwardly into the control housing 14, and also carried within said oil return reservoir is a centrifugal pump 18 having a motor 28. Carried within the control housing 14 is a mercury switch assembly 21, enclosed relay 29, and relay terminal block 45 15, which are operatively connected to a suitable source of electric power, and in the complete assembly a cover is provided for said housing.

45 In the operation of hydraulic elevators of the type here involved, when leakage oil from the collecting ring 10 is 50 deposited in the reservoir 13 it accumulates therein and as the level of said oil rises the float unit 17 rises therewith. When a predetermined volume of oil has accumulated within said reservoir the upright rod 19 on said ascending float unit engages and tips the pivotally-mounted switch 21 55 in the control housing 14. Upon the engagement of said mercury switch 21 the pump 18 in the return oil reservoir is actuated and commences pumping said accumulated leakage oil back into the elevator hydraulic system. When 60 said float returns to its original level the switch 21 pivots back to its normal position and the pump shuts off.

65 The above-described float switch and pump assembly is conventional in many modern hydraulic elevator installations, and is designed to ensure that the leakage oil is returned to the power unit hydraulic system so that there will always be sufficient oil in said system to permit safe operation of the elevator despite faulty packings or seals.

As hereinabove mentioned, however, conventional hydraulic elevators do not have means for detecting the presence of water in the oil return reservoir, and this can be a source of considerable trouble. If water finds its way into the return oil reservoir and is pumped into the hydraulic system it will saponify the oil and seriously impede the operation of the valves and other components, which can result in uncontrolled movement of the elevator. Not only is there always the danger of water from a burst water pipe or flood water in a building, but on hot, humid days a substantial quantity of water in the form of condensation forming on the plunger can create a hazard.

In accordance with the present invention there is mounted within the oil return reservoir 13 an electrical probe element which is designated generally by the numeral 22. As best appears in FIG. 2, said probe 22 includes a plastic intermediate portion 29 and a tubular body 23 formed of a suitable insulating material, the upper end of which is threaded and secured to the housing by a nut 27 (FIG. 1). Mounted in and projecting downwardly from said intermediate portion are a pair of spaced parallel copper arms 24 and 25 forming the electrodes of said probe, and soldered thereto and extending upwardly within said hollow body member 23 are electrical lead wires 26 which are connected to the relay mechanism in the control housing 14.

In the use of the present invention, when the elevator system is operative an electric current of predetermined value is constantly directed through the probe electrodes 24 and 25. Since oil is a poor conductor of electricity, however, the intensity of the current passing between said electrodes when the latter are immersed in oil is minimal. However, in the event water finds its way into the oil return reservoir and said downwardly-extending probe electrodes 24 and 25 are immersed or partially immersed in water, which is a relatively good electrical conductor, there will be a substantially-increased current flow. Said increased current flow through the probe electrodes is designed to energize the relay 20 which functions to prevent the operation of the pump 18, thereby eliminating the possibility of the water in said reservoir being pumped into the power unit hydraulic system. Simultaneously, said relay actuates a control switch which functions to prevent upward travel of the elevator, said elevator automatically descending to its lowermost level in order to permit the discharge of its passengers. The elevator doors are then closed and further operation is impossible until the trouble has been remedied.

The novel probe member 22 characterizing the present invention is suspended from the upper portion of the reservoir housing 13, as shown, and it will be noted that the electrodes 24-25 extend downwardly to a point closely adjacent the bottom of the oil return reservoir. Thus, in the event there is a minor amount of water at the bottom of said reservoir and a relatively larger quantity of oil floating on top thereof, said electrodes will nonetheless detect the presence of the water. As an additional precautionary feature, the oil inlet (not shown) for the pump 18 is positioned a substantial distance above the bottom of said reservoir to ensure that only the oil floating on the top thereof will be pumped back into the power unit hydraulic system if there is water in the reservoir.

From the foregoing detailed description it will be seen that the present invention provides a novel safety device for hydraulic elevators which is an important advancement in the art. As hereinbefore mentioned, many hydraulic elevators in present use include means for collecting and returning leakage oil to the power unit hydraulic system in order to ensure that there is always a sufficient quantity of oil to permit safe operation of the elevator, but heretofore there has been no means to protect against the entry of water into the oil system. Such water, whether it be condensate or surface water, can saponify the oil and impede the operation of the elevator, and can result in a disastrous accident. In accordance with the present invention, however, a sensing device is provided to detect the presence of water in the oil return reservoir, and to automatically prevent the operation of the oil return pump while simultaneously halting the elevator until necessary corrective measures can be taken to remedy the situation.

A further advantage of the present invention is that in the event the basement of the building is being inundated by flood water or a burst water main or the like, the presence of such water in the oil reservoir will be immediately detected by the sensing probe and the halting of the elevator will give early warning of the trouble, thereby permitting the high voltage junction boxes and other electrical components to be removed from the area before they are immersed in water and ruined, or before someone is accidentally electrocuted.

Still further advantages of the present invention are that it is completely reliable in operation, and it is relatively inexpensive in design and construction.

It is to be understood, of course, that the invention is not to be limited or confined to a structure identical in all respects to that illustrated and hereinbefore described. It is contemplated that numerous variations or modifications could be made therein while still incorporating the basic novelty of said invention, and it is intended to include herein not only the illustrated embodiment of the invention but also any and all modifications or variations both in the structure and intended uses thereof as may come within the spirit of said invention, and within the scope of the following claims.

30 What I claim is:

1. In a hydraulic power system including an oil reservoir, means for detecting the presence of water in said reservoir comprising: a probe element in said oil reservoir, said probe having a pair of spaced electrodes adapted to be immersed or partially immersed in a liquid contained in said reservoir; means connecting said probe electrodes to a source of electricity to permit a current to be passed between said electrodes, the greater electrical conductivity of water as compared to oil causing an increased current flow therebetween when said electrodes are immersed or partially immersed in water rather than oil; and electric sensing means operatively connected to said probe and adapted to detect the increased current flow through said probe electrodes in the event water is present in said oil reservoir.

2. In an elevator having a hydraulic power system, and having an oil return reservoir adapted to collect oil which leaks from said hydraulic system, there being a pump for pumping oil collected in said reservoir back into said hydraulic power system, a safety device for preventing the entry of water into said hydraulic system, comprising: a probe element in said oil return reservoir, said probe having a pair of spaced electrodes adapted to be immersed or partially immersed in a liquid collected in said reservoir; electrical lead wires connecting said probe electrodes to a source of electricity to permit a current to be passed between said electrodes, the greater electrical conductivity of water as compared to oil causing an increased current flow therebetween when said electrodes are immersed or partially immersed in water rather than oil; and electric control means operatively connected to said probe and adapted to be actuated by the increased current flow through said probe electrodes in the event of water in the oil reservoir to prevent the operation of said oil return pump.

3. The safety device recited in claim 2 and including means associated with said electric control means adapted to automatically halt the operation of the elevator in the event water is present in said oil reservoir.

4. The safety device recited in claim 2 wherein said probe element includes a hollow insulating body within which said lead wires are carried, and said probe electrodes being formed of flat, vertically-disposed parallel arms.

5. The safety device recited in claim 2 wherein said

probe electrodes extend downwardly to a point adjacent the bottom of the reservoir, whereby said probe will detect the presence of even a relatively small quantity of water in said reservoir.

6. The safety device recited in claim 2 wherein said oil return pump is provided with an inlet opening spaced a substantial distance above the bottom of the reservoir.
